UNITED STATES PATENT OFFICE.

HENRY D. CUMMINS, OF HUNT, NEW YORK.

CROSSOVER FOR RAILS.

1,021,574.

Specification of Letters Patent. Patented Mar. 26, 1912.

Application filed June 17, 1911. Serial No. 633,670.

To all whom it may concern:

Be it known that I, HENRY D. CUMMINS, a citizen of the United States of America, residing at Hunt, in the county of Livingston and State of New York, have invented 5 certain new and useful Improvements in Crossovers for Rails, of which the following is a specification, reference being had therein to the accompanying drawing.

10 This invention relates to crossovers for rails, and the primary object of my invention is to provide a crossover that can be easily placed in position to permit of a train or car passing from one track to another, whereby the train or car can easily pass around a wreck, derailment, washout or other obstruction that would otherwise delay the train or car.

Another object of this invention is to provide a temporary switch that can be carried by wrecking trains and easily and quickly placed in position for the rapid transfer of rolling stock.

A further object of this invention is to 25 accomplish the above results by a mechanical construction that is durable, inexpensive to manufacture and applicable to various types of railway tracks.

With the above and other objects in view, 30 the invention resides in the novel construction, combination and arrangement of parts to be hereinafter specifically described and then claimed.

Reference will now be had to the drawing, 35 wherein:—

Figure 1 is a plan of a crossover in accordance with this invention, Fig. 2 is a side elevation of the same, Fig. 3 is a longitudinal sectional view of the crossover, Fig. 4 40 is an enlarged perspective view of a tongue forming part of the crossover, and Fig. 5 is an enlarged perspective view of the crossover rail of the crossover.

The reference numeral 1 denotes ties or 45 sleepers supporting main rails 2 and 3 constituting a track, these rails being secured to the ties or sleepers in the ordinary and well known manner, preferably by spikes (not shown).

50 The reference numeral 4 denotes a switch rail mounted upon the ties 1, said switch rail having the base flanges 5 thereof cut away, as at 6 to engage the base flange 7 of the rail 3. The web and head of the rail. 55 4 extend over the base flange 7 and are cut away at an angle, as at 8 to engage the web

and head of the rail 3, said switch rail deflecting the movement of rolling stock, somewhat similar to an ordinary switch tongue.

The reference numeral 9 denotes a section 60 of rail mounted upon the ties or sleepers and disposed at an angle relatively to the rails 2 and 3, one end of said rail abutting the end of a switch rail 4 and the opposite end extending into proximity to the rail 2. 65

The reference numeral 10 denotes a crossover rail having the base flanges thereof mounted upon the ties and one end thereof abutting the end of the rail 9. The crossover rail has the web 12 thereof gradually 70 increasing in depth toward the rail 2 and decreasing in depth as the rail leaves the rail 2, said web and the base flange of said rail being cut away to provide an angularly disposed slot 12, which provides clearance for 75 the rail 2. On account of the depth of the web 11 of said rail, the head 13 of said rail is supported above the head of the rail 2, as best shown in Fig. 1.

The reference numeral 14 denotes a rail 80 having the base flange thereof cut away, as at 15 and the web, as at 16 whereby said rail can be placed at an angle against the outer side of the rail 2 opposite the switch rail 4. The rail 14 has the cut away end thereof 85 provided with a tongue 17 adapted to extend over the head of the rail 2, said tongue having a beveled surface 18 that permits of the wheels of rolling stock easily riding on to the tongue and then on to the rail 14. The 90 opposite end of the rail 14 abuts the end of a transfer rail 19 which is arranged in parallelism with the rail 9. Rails similar to the rails 4, 10 and 14 are used in connection with the track to which the rolling stock is to be 95 switched or transferred.

From the foregoing it will be observed that the crossover comprises three especially constructed rails for one track and similar rails for another track, these rails being used 100 in connection with sections of rails, the length of the ordinary sections of rails depending upon the angle of the crossover relatively to the tracks on to which rolling stock is to be transferred. 105

It is to be understood that the especially designed rails of the crossover device can be constructed for electric railway rails or any other type of rail, and while in the drawing there is illustrated a preferred embodiment 110 of the invention, it is to be understood that the structural elements thereof are suscep-

tible to such variations and modifications as fall within the scope of the appended claim.

What I claim is:—

A crossover comprising a pair of rail members 9 and 19, the former arranged exteriorly of and the latter between the main track rails, a switch rail 4 arranged between the main track rails, registering with the rail 9 and cut away at one end to engage the 10 inner side of the web and to overlap and engage the inner side of the base of one of the main track rails and further flush with the head of said main track rail, a rail 14 positioned exteriorly of the main track rails, 15 registering with the rail 19 and cut away at one end to provide a tongue extending on to the head of and further engaging the outer side of the web and the outer edge of and overlapping the inner side of the base of 20 the other track rail, said tongue gradually increasing in height upwardly, and a cross-

over rail registering with one end of the rail 9 and cut away intermediate its ends for the passage of that track rail upon which the head extends, said crossover rail having the 25 web thereof of sufficient height to support its head above the head of that track rail which extends through said crossover rail, said crossover rail engaging the inner and outer faces of that track rail upon which 30 said tongue extends and further engaging each side edge of and overlapping the base of said rail, said crossover rail gradually increasing in height from each end toward the center thereof.

In testimony whereof I affix my signature in the presence of two witnesses.

HENRY D. CUMMINS.
